UNITED STATES PATENT OFFICE

153,109

DESIGN FOR A BUILDING SIDING PANEL

Robert D. Bordeaux, Chicago, Ill., assignor to
Bird & Son, inc., East Walpole, Mass., a corpo-
ration of Massachusetts

Application July 8, 1948, Serial No. 147,448

Term of patent 14 years

(Cl. D68—1)

To all whom it may concern:

Be it known that I, Robert D. Bordeaux, a citizen of the United States, residing at Chicago, in the county of Cook and State of Illinois, have invented a new, original, and ornamental Design for a Building Siding Panel, of which the following is a specification, reference being had to the accompanying drawing, forming part thereof.

Fig. 1 is a perspective view of a building siding panel, embodying my new design; and

Fig. 2 is an enlarged fragmentary sectional view taken on line 2—2 of Fig. 1.

I claim:

The ornamental design for a building siding panel, as shown.

ROBERT D. BORDEAUX.
